UNITED STATES PATENT OFFICE.

CHARLES E. WEIBLEY, OF HARRISBURG, PENNSYLVANIA.

ROPE GUIDE FOR AWNINGS.

Application filed September 22, 1924. Serial No. 739,217.

To all whom it may concern:

Be it known that I, CHARLES E. WEIBLEY, a citizen of the United States, residing at Harrisburg, in the county of Dauphin and 5 State of Pennsylvania, have invented certain new and useful Improvements in Rope Guides for Awnings, of which the following is a specification.

This is an invention in rope guides for 10 awnings of the outside rigging type, and it consists of two main parts pivoted together, one adapted for attachment to the awning, and the other carrying a pulley and pivoted thereto.

15 The real object of the invention is to provide a pulley that will yield readily to the movements of the rope and compensate for any lack of alignment where two or more are used upon the awning as a guide per 20 rope. When thus constructed, they also compensate for any pulling and stretching of the awning, which is apt to take place with the different positions it takes as between the raised or lowered position of the awning.

25 In the accompanying drawings:—
Fig. 1 is a view in perspective;
Fig. 2 is an enlarged sectional view;
Fig. 3 is a side view partly in section;
Fig. 4 is a top plan view of the fastening 30 clip;

Fig. 5 is a top plan view of the base frame; and

Fig. 6 is an end view of the clip.

The numeral 1 represents a base-plate. 35 This is preferably made of sheet-metal cut in suitable proportions and having lugs 2 bent up from either side and provided with slots 3 at each end. The pulley frame is also preferably made of light sheet-metal and 40 comprises the sides 4 and the flanges 5, which are bent downwardly and embrace the lugs 2, to which they are pivotally attached by means of the pin or rivet 6. The pulley 7 turns on a pin 8 in the usual fashion.

45 A clip 9, preferably of sheet-metal, has the sharpened spurs 10 cut therefrom and bent upwardly as shown in Fig. 6.

In assembling the device, the base is placed upon the awning 11 in the position desired, 50 and the clip is placed therebeneath, and the

spurs are inserted through the fabric and through the slots 3, and bent to one side, preferably upwardly, as shown in Fig. 2, thus providing a simple and effective means for fastening the pulley frame in position on 55 the awning. The cord 12 passes beneath the pulley in the usual manner of the outside rigging type of awning pulley.

A pulley thus mounted has many advantages over the rigid type. The principal 60 advantage is that it gives or yields laterally with the rope, and automatically aligns itself with the rope when it is under tension, thus providing for any lack of exact alignment in the placing of the pulley on the awning, 65 and for laterally pulling, stretching or drawing of the awning, which is almost certain to take place in the average awning in the different positions it is required to take in raising and lowering the awning as well as 70 stretching it over its frame.

By my invention, in an effective way, the disadvantages are overcome by the adoption of simple and inexpensive mechanism.

I claim:

1. A rope guide for awnings, including a base, means of fastening the base to the awning, upstanding lugs and a frame made of a single piece of sheet metal and including sides and flanges, which latter are pivoted to the lugs, and a pulley rotatably connected with the sides forming a closed space through which a cord or rope is adapted to pass and be confined, whereby the rope or cord is freely engaged by the pulley irrespective of the accurate placement of the base and fastening means.

2. The combination with a base-plate having upturned oppositely located side lugs and provided with openings at its ends, a 90 pulley frame having sides and flanges turned in opposite directions, a pin for pivoting the flanges to the lugs, a pulley rotatably supported by the sides, a clip having spurs adapted to extend through the fabric 95 of an awning into the openings of the base, and to have its ends bent laterally, whereby to fasten the base-plate to the awning.

In testimony whereof I affix my signature.

CHARLES E. WEIBLEY.
